[57] ABSTRACT

A self-locking and sealing cap and bottle in which co-operating locking elements in the form of lugs and detents are provided on the matching threads of the cap and the bottle. A plurality of locking elements is provided on at least one of the bottle and cap, to thereby ensure that engagement of that one locking element with a corresponding element on the other member is achieved when the cap is tightly secured on the bottle. The locking lugs may be shaped with one edge tapered in the direction of rotation of the cap to permit ready rotation of the cap in that direction.

SAFETY LOCKING CAP

The present invention relates generally to bottles and closures therefor, and more particularly to an improved threaded bottle and mating cap for reliable locking thereon.

In my U.S. Pat. No. 3,435,978, there is disclosed a bottle and bottle cap combination in which the threads of the cap and the neck of the bottle each includes a co-operating locking element such that when the cap is threaded onto the neck of the bottle to thereby close the bottle, the mating bottle and neck threads frictionally engage to tighten the cap on the bottle and the locking elements cooperate to provide a supplemental, positive locking action of the cap on the bottle. Removal of the cap from the bottle and the removal of the contents of the bottle, such as by an overly inquisitive child, is made significantly more difficult. The safety implications of this result are apparent, particularly when harmful substances such as poisons, harsh cleansing fluids, and the like are contained in the bottle. The locking of the cap on the bottle in this manner is also of importance in preventing the loosening of the cap and the possible ensuing spillage of the bottle's contents such as during shipment of the bottle.

The locking arrangement disclosed in that patent has proven to be highly effective to achieve locking when the bottle neck is dimensioned such that engagement of the locking elements on the cap and bottle is achieved when the cap is tightly closed on the bottle, particularly since the locking is achieved without any deformation in either the frictionally engaging cap or bottle threads.

Plastic bottles, (e.g. polyethylene) with which the present invention, as well as that disclosed in my said patent, are both particularly amenable, are fabricated by a process which includes a molding operation. Upon the completion of the molding operation, the threaded neck portion is cut to establish a "standard" neck height for the bottle. As a result, however, of variations in the molding process, there may be differences in the neck heights of the completed bottles as well as in the dimensions of the bottle threads.

For this reason, it is difficult to accurately determine the relative position of the cap and bottle at which a secure, tight sealing engagement of the cap on the bottle will be achieved. For example, a variation in neck height of as little as 0.025 inch may be equivalent to a variation of one-eighth of a turn of the cap to effect cap tightening.

The locking engagement of the cap and bottle that may be achieved by the arrangement shown in said patent may thus occur when the cap has not yet reached its fully tightened, sealed position with respect to the bottle neck. Thus, the cap may be "locked" onto the bottle by virtue of the cooperating locking elements on the cap and bottle threads when the cap threads are only loosely engaged with those on the bottle neck. This may result in an undesirable leakage of the material contained in the bottle, particularly when the bottle is subjected to vibration such as when in shipment. As a result, the improved and simplified locking that could be obtained by the use of the bottle cap locking arrangement of my patent may not be utilized because of the possibility of leakage presented by manufacturing variations in the bottle dimensions.

It is thus an object of the invention to provide a locking arrangement in a threaded bottle and cap in which

locking is uniformly achieved when the cap is in a fully threaded or tightly closed and sealed condition.

It is a further object of the invention to provide a positive locking arrangement between a threaded bottle and cap in which at least one of a plurality of possible locking engagements is made when the cap is in its fully engaged position on the bottle.

It is another object of the invention to provide positive locking between a bottle and its accompanying closure cap while still ensuring tight, leak-proof engagement between the bottle and cap.

In the locking arrangement of the present invention, the thread of one of the bottle and the cap includes a plurality of locking elements. The other thread includes at least one cooperating locking element, such that when the cap is threaded into a sealing position with respect to the bottle, at least one pair of locking elements on the bottle and cap are in cooperating locking arrangement.

In an embodiment of the invention herein specifically disclosed, a plurality of cooperating or mating locking elements in the form of lugs and detents are provided on the threads of the cap and the bottle. The lugs are preferably shaped in a manner permitting either an increase or decrease in the amount of torque necessary to remove the cap from the bottle. In the embodiment of the invention herein specifically shown, the lugs have one tapered or sloping camming surface to permit ready rotation of the cap in the direction for closing, and a substantially vertical surface to prevent rotation of the cap in the opposite or opening direction.

In another embodiment of the invention, the number of locking elements on one of the cap and bottle members is an integral multiple of the number of locking elements in the other member. In this embodiment, the locking elements in both the bottle and the cap are equiangularly spaced about the periphery of the thread on which they are respectively formed. This arrangement ensures that when one pair of locking elements becomes engaged, all remaining ones of the lower number of locking elements are similarly engaged with respective ones of the other locking elements, to thereby provide additional locking action.

To the accomplishment of the above and to such further objects as may hereinafter appear, the present invention relates to a safety locking cap substantially as defined in the appended claims, and as described in the following specification taken together with the accompanying drawings in which:

FIG. 1 is a fragmentary view, partly in cross-section, of a spiral threaded bottle and complementary spiral threaded cap in accordance with one embodiment of the invention;

FIG. 2 is a view similar to FIG. 1 with the cap shown in its closed and locked position on the bottle;

FIG. 3 is a cross-sectional view as viewed in the direction of the arrows 3-3 of FIG. 2;

FIG. 4 is a cross-sectional view taken along the arcuate line 4-4 of FIG. 3;

FIG. 5 is a fragmentary cross-sectional view, on a relatively enlarged scale, taken along the line 5-5 of FIG. 2;

FIG. 6 is a transverse cross-sectional view of a locked threaded cap and bottle arrangement according to a second embodiment of the invention; and

FIG. 7 is a fragmentary cross-sectional view taken along line 7-7 of FIG. 6.

The locking cap and bottle arrangement of the present invention is an improvement over the locking arrangement disclosed in my said patent. That improvement ensures that locking of the cap on the bottle is uniformly achieved when the threaded cap is tightly screwed onto the neck of the bottle, irrespective of possible variations in the bottle dimensions. As broadly considered, in the cap locking arrangement of the invention, a plurality of locking elements is provided on one member, to wit, the bottle or cap, and at least one cooperating locking element is provided on the other member which is designed to engage with one of the plurality of locking elements on the first-mentioned member.

In the embodiment of the invention shown in FIGS. 1-5, a bottle 10, which may be advantageously formed of glass, metal or polyethylene or similar plastic material, has a neck 12 on which a spiral thread 14 is formed on its outer periphery as is conventional. A bottle cap 16, made preferably of a resilient material such as polyethylene or polypropylene and which is adapted to be screwed onto, tightened and then locked with the neck of the bottle 10, includes a complementary spiral thread 18 formed about its internal peripheral surface. Cap 16 is screwed onto the bottle neck until the top of the cap approaches the top of the neck, at which time the mating threads on the cap and bottle frictionally engage and tighten the cap and bottle. The cap locking arrangement of the present invention provides additional locking between cap 16 and bottle 10 and ensures that such locking occurs when the cap and bottle are in a tight and thus sealed engagement.

To this end, a plurality of cooperating locking elements are provided on at least the threads of either the cap or the bottle, and in the embodiment of the invention shown in FIGS. 1-5, each of the cap and bottle threads carry a plurality of locking elements. Thus, the bottle neck thread 14 is provided with a series of equiangularly spaced downwardly projecting lugs 20, and the internal cap thread 18 is provided with a plurality of equiangularly spaced detents or notches 22. As shown, the number of lugs formed on the bottle neck thread (here twelve spaced at approximately 30° intervals) is an integral multiple of the number of complementary lug receiving detents formed on the internal cap thread (here four spaced at 90° intervals).

In operation, the cap is placed over the neck of the bottle and rotated until the threads on the cap and bottle frictionally engage to create a tightening force. The lugs 20 are sufficiently small to pass between the cap threads until the cap is tightened on the bottle neck, at which time each detent on the cap thread receives one of the lugs on the bottle thread. That is, when any one of the lugs is received within a mating detent, the integral relation between the number of complementary lugs and detents and their respective equiangular spacing ensures that each detent will receive one locking lug. As a result, not only is locking ensured when the cap is tightly sealed, but the net locking effect is increased by the plurality of cooperating locking engagements that are achieved when the cap is tightened on the bottle.

Lugs 20 are shaped to provide a relatively low resistance to cap rotation when the cap is being twisted to its tightened or closed position on the cap, and to provide substantial resistance to cap rotation in the opposite or unlocking direction. As shown in FIG. 5, lugs 20,

as viewed in plan, are approximately in the form of a right triangle having a sloping side 24 and an almost normal side 26. When cap 16 is rotated in the direction of the arrow 28 in FIG. 5 to tighten and lock the cap on the bottle, the leading tapered sides of the lugs define camming surfaces which enable the cap to slide easily over the lugs until the cap is tightened on the bottle, and one of the lugs on the bottle thread is received within one of the complementary detents formed in the cap thread. Removal of the cap from the bottle by twisting the cap in the opposite direction, however, is significantly impeded by the engagement of the vertical side of the lug against the wall of the detent in which it is at that time received. By shaping the locking lug in this manner, a "ratcheting" action is achieved which permits the cap to be rotated freely in only one direction.

The embodiment of the invention shown in FIGS. 6 and 7 also ensures locking by the engagement of at least one lug in a complementary detent when the cap is tightened on the bottle. In this embodiment, a plurality of spaced lugs 20a and cooperating detents 22a are respectively provided over only a portion of the thread periphery on both the bottle neck 12a and cap 16a. As shown in FIG. 6, the number of lugs on the bottle is the same, here five, as the number of detents formed in the cap thread. The lugs and detents are respectively positioned on the bottle and cap threads, such that at least one pair of lugs and detents will be in confronting relationship when the cap is tightly threaded onto the bottle, to thereby achieve secure locking of the cap on the bottle.

It may occur, in this embodiment, depending on the dimensions of the cap and bottle threads, that when the cap is rotated to its lowermost tightened position on the bottle, additional pairs of lugs and detents will be in registration and will be engaged in a manner to achieve locking of the cap. Although the engagement of a single lug and detent pair is capable of producing locking of the cap, the engagement of the additional lugs and detents when achieved provides still further locking. The shape of the lugs in the embodiment of FIGS. 6 and 7 is preferably similar to that described with reference to the embodiment of FIGS. 1-5, to permit relatively unobstructed cap rotation in only the locking direction.

The improved cap locking arrangement of the invention thus ensures the locking engagement of at least one pair of cooperating locking elements respectively provided on the cap and bottle threads when the cap is tightly threaded onto the bottle. The locking action is desired to prevent access to the contents of the bottle by a child, or the loosening of the bottle with the resultant spillage when the bottle is in transit. The arrangement of the present invention, in contrast to the prior locking arrangements as exemplified in my said patent, is uniformly achieved when the cap is tightly secured on the bottle. This desirable result could not always be achieved in the prior cap locking arrangements for the reasons set forth above, so that the present invention represents a significant improvement over the previous designs.

While the invention has been herein described with respect to specific embodiments in which the cap and bottle each include a plurality of locking elements (lugs or detents), similar cap locking can be achieved by providing a single element on either the cap or bottle and a plurality of cooperating elements on the other mem-

ber. Moreover, while in the embodiments herein shown, the lugs are formed on the bottle neck threads, and the detents are formed in the cap threads, this arrangement could be reversed with the same results as described above.

Thus while several embodiments of the present invention have been herein specifically described, it will be apparent that modifications may be made therein without departing from the spirit and scope of the invention.

I claim:

1. A locking arrangement for a container and an accompanying cap therefor, comprising a spiral thread formed on the neck of said container and a complementary spiral thread formed on the interior surface of said cap for functionally engaging said container thread, a plurality of first locking elements formed on the thread of one of said cap and container, and a plurality of second locking elements formed on the complementary thread on the other of said cap and con-

20 tainer for respectively receiving said plurality of first locking elements in a locking relation when said cap is tightly threaded onto said container by the engagement of said complementary spiral threads, said first and second plurality of locking elements being respectively substantially equiangularly spaced about at least a portion of the periphery of said neck and container, the number of one of said first and second locking elements being an integral multiple of the other of said first and second locking elements.

15 2. The locking arrangement of claim 1, in which one of said first and second locking elements comprises a lug and the other of said first and second locking elements includes a detent for receiving said lug, said lug including a sloping camming portion and a substantially vertical portion for permitting ready rotation of said cap on said bottle in only the direction for thread engagement.
